UNITED STATES PATENT OFFICE.

LAWRENCE HOLMES, OF LOS ANGELES, CALIFORNIA.

UPENDING BED.

1,102,585.

Specification of Letters Patent.

Patented July 7, 1914.

Application filed August 27, 1913. Serial No. 786,995.

To all whom it may concern:

Be it known that I, LAWRENCE HOLMES, a citizen of the United States, residing at Los Angeles, in the county of Los Angeles and State of California, have invented a new and useful Upending Bed, of which the following is a specification.

This invention relates to an up-ending bed which may be variously mounted, but is more particularly designed to be applied to an up-ending bed mounted on a rolling base or pedestal which supports the bed when up-ended into storing position as set forth in my co-pending application for U. S. patent on independent storage bed, Serial No. 786,994, filed August 27, 1913.

Objects of the invention are as follows:— to provide a novel, neat, simple, light, compact, inexpensive, easily foldable bed construction in which the up-endable section of the bedstead is counterbalanced; in which means are provided to exert a strong force to resist the final descent of the bed frame and to give the initial upward start to the bed frame; to make the bed stable and absolutely rigid and firmly supported upon the floor in any position for use; to automatically extend and retract supplementary supporting legs of the bedstead as the frame section is lowered to and raised out of position for use; to construct the bed with a practical head-board to support the pillows and the end of the mattress; and to hold the up-endable portion upright when folded.

Other objects and advantages may appear from the subjoined detail description.

The accompanying drawings illustrate the invention.

Figure 1 is a broken front elevation of the bed in storing position. Fig. 2 is a broken side elevation from the left of Fig. 1. Fig. 3 is a side elevation of the bed down ready for use. Fig. 4 is a perspective view of one of the cams detached and viewed from the inner side. Fig. 5 is a broken sectional elevation from line indicated at $\alpha\beta$, Fig. 1. Fig. 6 is a fragmental detail showing the cam action.

One section of the bedstead consists of an upright frame formed of two standards 1, 2, a top bar 3 connecting the tops of the standards and a bottom bar 4 connecting the bottoms of said standards at the rear edges thereof. Said standards are enlarged at their base by forward extensions 5. Said frame is pivoted on a vertical axis by a

pin 6 on an upright post 7 that is fixed by a coupling 8 to a base comprising a horizontal frame 9 mounted on trundle wheels 10 which may be of any suitable number, three being employed in the form shown in the drawings. At the front of the basal extensions 5 of the standards, guide means in the form of loops 12, one above another, are provided to receive vertically movable legs 13 that slide up and down in said loops and that are adapted to engage the floor when not supported. An up-endable bedstead section 14 is pivoted near one end by horizontal pivots 15, to the fronts of the upper ends of the front extensions of the standards, so that said bedstead section may be up-ended and lowered on the horizontal pivotal axis at 15, which is just above the level of and is rearwardly of the legs 13. Said up-endable bedstead section 14 is provided with outwardly and downwardly extending cams, each having an abrupt face 16 preferably extending at right angles to the shorter ends 17 of the side rails of the up-endable section 14. Said pivots 15 are rearward of the produced axes of the legs 13 and said cams are arranged so that said abrupt face 16 will rest on the upper ends of the vertically movable legs 13 and will operate to depress said legs 13 when the bedstead section 14 is moved downward. An arc face 18 of the cam extending upward and around from the abrupt face 16 concentric with the pivot 15 maintains downward pressure on the legs as 90 the bedstead section 14 comes to horizontal position. An outrigger arm 19 is mounted in pivotal relation to the upright bedstead section formed by the standards and cross-bars; said arm being pivoted by a bolt 20 to the lower cross-bar 4 and extending outwardly beneath the stay 21 that is fastened to the legs 13. Said out-rigger arm 19 is provided with a caster 22 to roll on the floor and the stay 21 is arranged to engage or contact with the top of the out-rigger arm 19 when the legs 13 are depressed, so that, in the act of lowering the bedstead section 14, said arm 19 is held down though its rear end may be sprung up slightly as suggested by dot and dash lines at the left in Fig. 5.

A head-board 23 is in pivotal relation with the up-endable section 14, being pivotally connected therewith by horizontal pivots 24 at the bottom of the head-board; said pivots extending through guard-plates 25

that are fixed to the shorter ends 17 of the side rails of the up-endable bedstead section. The upper end of said head-board is formed by a transverse bar 26 which is slideable up and down on a guide way formed by the post 7 and is loosely connected to said post by a sliding connection as the chain 27, extending around the post 7 and connected with said transverse bar 26, so that as the 5 up-endable bedstead section 14 is moved on its axis 15 the head-board will be moved up as the section 14 is lowered, and vice versa. Spring means, as the helical springs 28, extend between and connect with the upper 10 end of the head-board and a portion of the upright frame beneath said head-board; said springs being connected at their upper ends to the transverse bar 26 of the head-board and at their lower ends to the cross-bar 4 of the frame, so that as the bedstead section 14 is lowered the helical springs 28 are stretched, thus to exert force to prevent too rapid lowering of the longer arm of the bedstead section 14. At the same time the cam 15 faces 16 and 18 successively operate to force and hold the legs 13 and stay 21 down to act on the arm 19. This also incidentally tends to uplift the front extensions 5. During the 20 operation of up-ending the section 14, the springs 28 act downward through the head-board 23, the guard plate 25 and lower end 17 of bedstead section 14 to assist in the up-ending operation.

The plates 25 afford guards to retain the 25 edges of the bedding, not shown, to prevent it from rubbing on the standards. The bed-guard 29, Figs. 1, 2 and 3 is pivotally mounted at 30 on the guard plates 25 above and rearwardly from the rail ends 17 and from 30 the pivots 24 of the head-board, and is provided with a runner 31 that runs down the post 7 and that is loosely connected therewith by the loop 32 corresponding to the loop 27.

45 The stay 21 is provided with an ear 33 having a vertical slot 34 in which is engaged one end of a connecting rod 35, the other end of which engages a brace 36 which connects the swinging legs 37 that are fixed to a horizontal axis 38, carried by loops 39 fixed to a cross-bar 40 of the bedstead section 14, thus forming a loose connection between the stay 21 and the cross-bar 40 at the foot of the bed; said connection being of such length as 50 to lift the stay 21 and the vertically movable legs 13 at the up-ending movement of the bedstead section 14, and vice versa, allowing said vertically movable legs to descend as the bedstead section 14 descends; the slot 34 55 allowing for lost motion, so that the legs will not be moved up too forcibly against the cams.

It is found in actual practice that as the 60 bedstead section 14 lowers, upward pressure is thus brought upon the pivot 15 by action

of the cam 18 on the legs 13 and there is a slight upward movement of the standards 1, 2 from the position said standards occupy when the section 14 is up-ended. This movement may be accommodated in the 70 form shown by making the top bar 3 sufficiently resilient and yielding to bow down slightly under the weight of the up-ended bedstead, as shown in Figs. 1 and 2. All of such weight, including that of the standards 75 1, 2, the up-endable frame 14, and the bed bottom and bedding, not shown, is borne by the center of the supporting bar 3 which rests on post 7. When the bed is lowered, as in Fig. 3, the top bar 3 springs back to 80 straight horizontal position.

I claim:

1. A bed comprising an upright frame, a bedstead section pivoted near one end to said frame, a head-board pivotally connected to said end and movable up and down in said frame, and spring means connecting the head-board with a portion of said frame below the head-board, whereby the upward movement of the head-board as the bedstead 85 section is lowered on its pivots extends the springs.

2. The combination of an upright frame; a bedstead section pivotally mounted near one end on said frame; a head-board section 95 pivotally connected to said end and movable up and down in said frame, helical springs connected at the upper ends with the head-board and at the lower ends with the frame; and upper guide means in the frame to guide 100 the upper end of the head-board; the tension of the springs tending to hold the head-board down thereby to assist in up-ending the bedstead section.

3. The combination with a frame comprising two standards having forward extensions at their bases; and means connecting vertical guides on said extensions; legs mounted in said guides; a bedstead section pivotally mounted near one end on said 105 standards; cams on said bedstead section to engage said legs to depress the same; and spring means in operative connection with said bedstead section and said frame to operate with said cam to resist lowering 110 the bedstead section to horizontal position.

4. The combination of an upright bedstead section, an up-endable bedstead section pivotally mounted thereon, a head-board in pivotal relation to the up-endable bedstead section and movable up and down in the upright section, a guide for the upper end of the head-board; and spring means connecting the head-board with the lower portion of the upright bedstead section.

5. An upright bedstead section, an up-endable bed section pivoted to the upright section, a head-board in pivotal relation to the up-endable bedstead section, and a bedding guard pivoted to the bedstead section,

- said head-board and bedding guard moving up and down in the bedstead section.
6. An upright bedstead section, an up-endable bedstead section pivoted to the up-right section, a head-board in pivotal relation to the up-endable bedstead section, and a bedding guard pivoted to the up-endable section, said head-board and bedding guard moving up and down in the upright bedstead section, means to guide the upper end of the head-board in a vertical path, and means to guide the upper end of the bedding guard.
7. A base, a bedstead comprising an up-right section mounted on the base, an up-endable section pivoted on the upright section, a cam on the up-endable section and vertically movable legs compressible by the cam, one end of each leg being mounted on the upright section and the other end being supported by the floor.
8. The combination of an upright bedstead section, an up-endable bedstead section pivoted thereon, vertically movable legs mounted on the upright section, a cam on the up-endable section having an

abrupt face adapted to engage the upper ends of the vertically movable legs to depress the same and also having a face extending around from said abrupt face and adapted to ride over the upper ends of said legs to maintain the legs in depressed position.

9. The combination with an upright frame, of an up-endable bedstead section pivoted to said frame on a horizontal axis; a head-board movable up and down in said frame and pivoted to the bedstead section at one side of said axis so as to move down and up as said section is raised and lowered; and springs extending between and connected with the head-board and a portion of said frame below the head-board and tending to force the head-board down to assist in up-ending said bedstead section.

In testimony whereof, I have hereunto set my hand at Los Angeles, California, this 22d day of August, 1913.

LAWRENCE HOLMES.
